CLAIM

The ornamental design of the stamp, as shown and described.

DESCRIPTION

FIG. 1 is a perspective view of a design for a stamp showing my design;

FIG. 2 is a front elevation thereof;

FIG. 3 is a back elevation thereof;

FIG. 4 is a left side elevation thereof;

FIG. 5 is a right side elevation thereof; and,

FIG. 6 is a top plan view thereof.

The portions of the stamp arrangement that are not shown in the drawing do not form any part of the claimed design.
